(57) **CLAIM**

The ornamental design for a culvert cover, as shown and described.

DESCRIPTION

FIG. 1 is a front view of the culvert cover of the present invention;

FIG. 2 is a cross-sectional side view of the culvert cover as taken along line 2-2 in FIG. 1;

FIG. 3 is a view of the right side of the culvert cover of the present invention, the left side being a mirror image;

FIG. 4 is a top view of the culvert cover of the present invention;

FIG. 5 is a rear view of the culvert cover of the present invention;

FIG. 6 is a rear perspective view of the culvert cover of the present invention; and,

FIG. 7 is a front perspective view of the culvert cover of the present invention.
